UNITED STATES PATENT OFFICE

2,687,892

GRAIN DISTRIBUTOR

John Kinsella, Merna, Ill.

Application July 25, 1951, Serial No. 238,554

4 Claims. (Cl. 275—15)

1

This invention relates to new and useful improvements in grain distributors and the primary object of the present invention is to provide a device mountable within a grain bin at the filling opening thereof to effectively scatter grain as the grain is dropped through the filling opening by a conveyor or the like.

Another important object of the present invention is to provide a grain distributor for grain bins involving a vertically adjustable deflector mounted beneath an inverted conical hopper to rotate in response to grain striking the sloping wall of the deflector, said deflector having an upper conical tip adapted to be adjusted to enter the center of a stream of grain passing from the hopper to increase the scattering or deflecting function of said deflector.

A further object of the present invention is to provide a grain distributor of the aforementioned character that is quickly and readily applied to or removed from a grain bin in a convenient manner and which requires no service for its successful operation once the conical tip of the deflector has been adjusted to the center of the stream of grain passing from the hopper.

A still further aim of the present invention is to provide a grain distributor that is extremely simple and practical in construction, strong and reliable in use, efficient and durable in operation, inexpensive to manufacture, install and service, and otherwise well adapted for the purposes for which the same is intended.

Other objects and advantages reside in the details of construction and operation as more fully hereinafter described and claimed, references being had to the accompanying drawings forming part hereof, wherein like numerals refer to like parts throughout, and in which:

Figure 1 is an elevational view of the present invention mounted on a grain bin (shown in dotted lines);

Figure 2 is a plan view of Figure 1;

Figure 3 is an enlarged vertical sectional view taken substantially on the plane of section line 3—3 of Figure 2;

Figure 4 is an enlarged bottom plan view of Figure 1; and

Figure 5 is an enlarged detail vertical sectional view taken substantially on the plane of section line 5—5 of Figure 1.

Referring now to the drawings in detail, wherein for the purpose of illustration, there is disclosed a preferred embodiment of the present invention, the numeral 10 represents a base member preferably in the form of an angle iron ring

2

to which a plurality of circumferentially spaced radially projecting, U-shaped arms 12 are fixed by welding or the like.

The arms 12 slidably support fasteners 14 on which angle iron cleats 16 are mounted. The cleats 16 extend transversely across the arms 12 and the fasteners 14 are manually tightened to adjust the cleats 16 radially of the ring 10 and against the wall of an opening 18 in a hopper bin 20 upon which the arms 12 rest.

The vertical flange of ring 10 enters the major end of an inverted conical hopper 22 and is suitably fixed thereto by welding, fasteners or the like to support the hopper in a vertical position within a conventional grain bin, such as 20.

The upper ends of a group of vertical sleeves 24 are fixed by welding or the like between the legs of the U-shaped arms 12. The lower ends of the sleeves 24 are formed with threaded transverse apertures 26 that receivably engage set screws 28. The longer vertical legs of L-shaped hangers 30 are slidably received in the sleeves 24 and are maintained in vertically adjusted position upon manual tightening of the set screws 28.

The shorter legs of the hangers 30 are disposed radially of the hopper 22 and horizontally below the minor discharge end of the hopper. A plate 32 overlies the adjacent inner ends of these shorter legs and is welded thereto, as shown best in Figure 5 of the drawings. The lower end of a tubular post 34 is welded to and rises from the center of plate 32 and freely rotatably supports a deflector designated generally by the numeral 36.

Deflector 36 comprises a spiral-like member having a downwardly and outwardly sloping wall 38 that progressively increases radially outwardly from the axis of the spiral-like member in a clockwise direction. The upper end of wall 38 is cast with a frusto-conical tip portion 40 having a recess 42 in its undersurface that accommodates the upper end of post 34, a bearing race 44, an upper washer 46 and a lower washer 48.

A conical tip 50, forming a continuation of or the upper half of portion 40, is disposed above portion 40 and is formed with a seat 52 in its underside that receives the upper end of a rod 54 that extends upwardly through the plate 32, post 34 and portion 40 and which is removably secured to the plate 32 as at 55. Upper and lower guides 56 and 58 are positioned in the post 34 and surround the rod 54. Thus, the deflector 36 is freely rotatably supported on the post 34.

Means is provided whereby the deflector will

3

rotate in response to grain passing through the discharge end of the hopper and this means comprises vertically inclined fins 60 suitably secured to the wall 38 to be engaged by grain passing from the hopper. As the grain, gravitating from the hopper, strikes the fins 60, rotation will be imparted to the deflector and as the deflector rotates grain will strike the wall 38 to be deflected varying distances from the deflector.

In order to permit the desired rotation of the deflector, the hangers 30 are adjusted until the tip 50 is centered in the stream of grain leaving the discharge end of the hopper since the grain leaving the hopper may pass through only a portion of the opening in the lower end of the hopper.

It should be noted that through use of the present grain distributor, thousands of bushels of grain will be saved that are usually spoiled each year because of unequal distribution of foreign materials in grains, such as chaff, dirt, wheat seeds, cracked grain, etc. The invention will evenly distribute grain including dirt and other foreign matter so that the same will not be concentrated at one point to cause undesirable heating of grain stored in bins.

A frusto-conical attachment A, see Figure 3, is removably secured about the lower end of the hopper 22 to gradually reduce the lower portion of the hopper and to keep small flows of grain concentrated on the cone 50, thereby obtaining better distribution of grain from the hopper when flow is slow.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention what is claimed as new is:

1. A grain distributor comprising a base adapted to be mounted in the filling opening in a grain bin and including a plurality of radial arms, a hopper mounted on the base and having a lower discharge end, a grain deflector underlying said discharge end, vertically adjustable L-shaped

hangers fixed to said arms, a plate fixed on said hangers, a hollow post rising rigidly from said plate and having the deflector rotatably mounted on its upper end, and a rod rotatably extended through said post and having one end fixed to said deflector and its other end rotatably secured in said plate to secure the deflector in place.

2. A grain distributor comprising a base adapted to be mounted in the filling opening in a grain bin, a hopper mounted on the base and having a lower discharge end, a rotatable grain deflector underlying said discharge end, a plurality of vertical sleeves fixed to said base, a group of L-shaped hangers having their longer legs slidably received in said sleeves, set screws carried by the sleeves engaging said longer legs to adjust the hangers in the sleeves, a plate fixed to and joining the shorter legs of said hangers, and a post rising from the plate and rotatably supporting the deflector.

3. A grain distributor comprising a base adapted to be mounted at the filling opening of a grain bin, means carried by the base for retaining the latter at the filling opening in a grain bin, a plurality of vertical sleeves fixed to the base, a group of L-shaped hangers having their longer legs slidably and adjustably received in the sleeves and their shorter legs extending toward each other and disposed horizontally below the base, a plate fixed to and joining the shorter legs of said hangers, an inverted conical hopper supported on the base with its lower end disposed directly over the plate, a post rising from the plate, and a deflector rotatably supported on the post beneath the hopper.

4. The combination of claim 3 wherein said retaining means includes a group of radially projecting arms, and cleats slidably and adjustably carried by said arms.
